CUFF MACHINE

Hermon H. Woodward, Troy, and Alpha H. Wright, Albany, N. Y., assignors to Hall, Hartwell & Co., Inc., Troy, N. Y., a corporation of New York

Application May 2, 1931, Serial No. 534,654

7 Claims. (Cl. 223—55)

Our invention relates to machines for pressing cuffs during their process of manufacture. It is illustrated in the accompanying drawings, wherein:

- 5 Fig. 1 is a plan view of our machine;
 Fig. 2 is a front view of the device partly in section;
 Fig. 3 shows the presser;
 Figs. 4 to 6 show enlarged details.
 10 Our machine comprises a cuff carrier on which a cuff is stretched out flat ready for pressing, and the said carrier, with the cuff carried thereon, is then moved forward to place the cuff under a heavy press which thereupon descends and presses
 15 it.

The carrier consists of a bar A, shown in Figs. 1, 2 and 3, mounted on a slide which is arranged to reciprocate, as appears in Figs. 1, 2 and 3, towards or from a press B on a pair of transverse ways a, a. On the said bar A are two flat plates or wings, C¹, C², formed of thin plates shaped to the contour of an ordinary cuff and formed with loops D, D, on their under side. These loops embrace the bar A and permit the two plates C¹, C² to glide thereon with relation to each other. The bar A and the ways a, a are so constructed and arranged that said bar is held against rotation at all times, thereby maintaining the cuff plates C¹, C² in parallel relation with said ways at 20 all times during reciprocation of said bar. Wing C² is temporarily secured to bar A by means of screws d, d, which pass down through the wing C² and enter a pair of holes in the bar A. There are a series of these holes in bar A, so that the position of the wing C² thereon may be adjusted back and forth with respect to the bar A according to the size of the cuff that is being operated on. C¹ is a similar wing, corresponding to the opposite end of the cuff. It is also provided with a loop D and slides on the opposite end of bar A. A spring F tends to press plate C² along the bar A. A roller G on the under side of plate C¹ is, by spring F, brought against a fixed diagonal plate E which tends, as the carrier bar A is moved back away from the press B, to force plate C¹ slightly towards plate C². Thus when the carrier bar A, together with the plates C¹ and C², reach their rear position, away from the press B, those plates, C¹ and C², are a little closer together. Thus it is easy to slip the cuff over the two plates. Then when the plates start towards the press, they automatically spread apart under the influence of spring F as the roller G separates from the diagonal cam-plate E. This serves to spread the cuff tightly between the

plates. It should be mentioned that the plates C¹ and C² lie underneath only one ply of the cuff and therefore forms a slight bead on each end of the cuff and around the rounded corners. Moreover, the cuff applied to the plates has been sewed and then turned inside out. In addition, the cuff plate C² is secured adjustably to the bar A by the aforesaid screws d, d entering the holes in A. This provides for the permanent adjustment of the plates C¹ and C² while the aforesaid spring F provides for their temporary spreading apart for applying the cuff to them.

On the presser side, Fig. 1, P represents the fixed bottom plate on which is also a fixed cross bar, or guide-plate H, against which the leading edge of the cuff abuts as it moves up to the press and is there held while the plate R, carried by a plunger, descends and presses the cuff as it lies on the base plate P. On the aforesaid guide-plate H there is a slight notch h formed along its front edge, as appears in Figs. 1, 2 and 3. This notch h receives the edge of the cuff along the front and forms a slight bead thereon corresponding to the beading formed on the cuff ends by the spreading pressure of plates C¹ and C². The bed plate is heated in a well known manner by a heater K (Fig. 1) embedded therein. The operation includes the application of the cuff to the plates C¹, C², followed by the forward movement of said plates and the cuff thereon up towards and under the press, and then the descent of the press on the stretched out plates. Then the press is raised, the cuff is drawn back together with the plates and removed preparatory to the pressing of the next cuff.

What we claim as new and desire to secure by Letters Patent is:

1. A cuff pressing machine comprising a press, ways projecting from said press and supported thereby, a carrier slidably mounted in said ways so as to move toward and away from said press, a transverse bar mounted on said carrier member, a stationary cuff spreader plate mounted on said bar, a second cuff spreader plate slidably mounted on said bar, a spring reacting between said carrier member and the movable cuff spreader plate to normally move said plate away from the stationary plate, a stop bar normally engaging said movable plate so as to limit movement thereof under tension of said spring, said stop bar being inclined so as to progressively control movement of the second plate under tension of said spring as the carrier moves toward and from the press, said cuff spreader plates being shaped to fit within a cuff.

2. A cuff pressing machine comprising a press, a carrier member movable toward and from the press, a transversely disposed bar rigidly anchored to said carrier member and provided with free end portions projected laterally from the carrier member, a cuff spreader plate anchored in a normally fixed position to one free end portion of said bar, a second cuff spreader plate slidably mounted on the other free end of said bar in such manner as to be adjustable with respect to the first plate, a spring interposed between said slideable cuff spreader plate and said carrier member in such manner as to normally move the last mentioned cuff spreader plate from the other cuff spreader plate, and means for limiting movement of the slideable cuff spreader plate away from the other plate, said last mentioned means including means for moving the slideable cuff spreader plate against the tension of said spring during movement of the carrier member away from said press.

3. A cuff pressing machine comprising a press, a carrier member movable toward and from the press, a transversely disposed bar rigidly anchored to said carrier member and provided with free end portions projected laterally from the carrier member, a cuff spreader plate anchored in a normally fixed position on one free end portion of said bar, a second cuff spreader plate slidably mounted on the other free end of said bar in such manner as to be adjustable relative to the fixed spreader plate, a spring located beneath said bar and interposed between the slideable cuff spreader plate and the carrier member in such manner as to normally move the slideable cuff spreader plate away from the fixed spreader plate, and means for limiting slideable movement of the slideable cuff spreader plate away from the fixed spreader plate under the tension of said spring, said last mentioned means including means for gradually moving the slideable cuff spreader plate against the tension of said spring during movement of the carrier member away from said press.

4. A cuff pressing machine comprising, a press, a carrier member movable toward and from the press, a transversely disposed bar rigidly anchored to said carrier member and provided with free end portions projected laterally from the carrier member, a cuff spreader plate anchored in a normally fixed position on one free end portion of said bar, a second cuff spreader plate slidably mounted on the other free end of said bar in such manner as to be adjustable relative to the fixed spreader plate, a spring interposed between the slideable cuff spreader plate and said carrier member in such manner as to normally move the slideable cuff spreader plate away from the fixed cuff spreader plate, a depending stop member carried

by the slideable cuff spreader plate, and a stop bar having an inclined surface diagonally disposed relative to the path of movement of said carrier member and so positioned as to serve as a graduated abutment for said depending stop member.

5. A cuff pressing machine comprising a press, parallel guides supported in front of said press, a carrier slidably mounted in said guides, a transversely disposed bar rigidly anchored to said carrier member and provided with free end portions projected laterally from the carrier member in such manner as to extend over said guides, a cuff spreader plate anchored in a normally fixed position to one free end portion of the bar, a second cuff spreader plate slidably mounted on the other free end of said bar in such manner as to be adjustable with respect to the other fixed plate, and means constructed and arranged to move the slideable cuff spreader plate toward and from the fixed cuff spreader plate during movement of the carrier toward and from said press.

6. A cuff pressing machine comprising a press, guide means in front of said press, a carrier engaging said guide means and movable toward and from the press, a transversely disposed flat bar fixedly anchored to said carrier member and provided with free end portions projected laterally from the carrier member, a cuff spreader plate anchored in a normally fixed position to one free end portion of the bar, a second cuff spreader plate slidably mounted on the other free end of the bar, means for yieldably moving the slideable cuff spreader plate away from the fixed cuff spreader plate, and means for limiting movement of the slideable cuff spreader plate away from the fixed cuff spreader plate, said means being constructed and arranged to permit continuous sliding movement during movement of the carrier toward and from the press.

7. A cuff pressing machine comprising a press, guides extending from the front of said press, a carrier slidably mounted in said guides and movable toward and from the press, a flat bar fixedly secured to the top of said carrier, said bar having a plurality of openings in one end, a cuff spreader plate adjustably mounted on the last mentioned end of said bar, means engaging any of said openings in such manner as to fixedly anchor said cuff spreader plate, a second cuff spreader plate slidably mounted on the other end of the bar, and means for effecting continuous slideable movement of the slideable cuff spreader plate toward or from the fixed spreader plate during the travel of said carrier toward and from the press.
